DENTAL MATRIX CLAMP

Donald R. Christie and Merton M. Bottemiller,
Wadena, Minn.

Application March 17, 1949, Serial No. 81,876

15 Claims. (Cl. 32—63)

1

The present invention is particularly concerned with a dental matrix clamp of the type in which a matrix ribbon clamps snugly around a tooth during the fitting of a cavity. These ribbons are highly flexible in order to enable them to conform closely with the contour of the teeth, so that the filling will not project beyond the surface of the tooth. Nevertheless, due to the curvature and taper of the normal tooth, it is impossible for the ribbon to conform closely enough to the contour of the tooth unless some special means is provided to permit turning and unless the ribbon does conform closely, the filling will project beyond the surface of the tooth and tend to retain food. Consequently, various arrangements have been developed in an attempt to enable the matrix ribbon to adjust itself to the taper of the tooth. These prior arrangements have, however, all lacked the ability to conform to the varying degrees of taper and curvature found with a normal tooth. A further defect with prior matrix clamps is that it is possible to fill only one tooth at a time since no provision is made for simultaneously applying a matrix band to two teeth. Since cavities often occur in adjacent teeth, the lack of a provision for applying a matrix band simultaneously to more than one tooth results in loss of time of both the dentist and the patient.

An object of the present invention is to provide a matrix clamp which permits the matrix ribbon to more closely conform to the contour of the tooth despite varying amounts of taper and curvature of the tooth.

A more specific object of the invention is to provide a matrix clamp in which the matrix ribbon is guided by a plurality of freely tiltable guides, the points of tilting of which may be moved.

A still further object of the invention is to provide a matrix clamp in which provision is made for simultaneously clamping the matrix ribbon closely about a plurality of teeth so cavities in adjoining teeth may be simultaneously filled.

A further object of the invention is to provide a matrix clamp, such as set forth in the preceding object, in which provision is made for the matrix ribbon closely conforming to the various teeth about which the matrix ribbon is clamped despite differences in the taper of the teeth.

A further object of the invention is to provide such a matrix clamp for a plurality of teeth in which the matrix ribbon is maintained in uniform tension about all of the teeth surrounded by the matrix ribbon.

A further object of the invention is to provide a matrix clamp in which a provision is made for more readily removing the ribbon for inspection and cleaning purposes.

2

Other objects of the invention will be apparent from the accompanying specification, claims, and drawing of which

Figure 1 is a top plan view of several normal teeth of a lower jaw, showing our improved matrix clamp cooperating with a matrix ribbon applied to two of the teeth;

Figure 2 is an inside elevation of the teeth and a front elevation of the clamp of Figure 1;

Figure 3 is a top plan view of several normal teeth of a lower jaw, showing our improved matrix clamp partially in section, cooperating with a matrix ribbon applied to merely one of the teeth;

Figure 4 is a side elevational view of the matrix clamp without the matrix ribbon;

Figure 5 is a sectional view taken along the line 5—5, to show the construction of one of the ribbon guides;

Figures 6 and 7 are top sectional view of the ribbon clamp on a somewhat larger scale than that of Figures 1 to 4; and

Figures 8 and 9 are views of two modifications of a pivotable ribbon guide.

Referring to the drawing, our improved matrix clamp comprises a body member 10 formed of sheet metal and having upturned side flange portions 11 and 12. Member 10 is cut away between the flanges 11 and 12 for substantially the full length of the flanges. Disposed between the flanges 11 and 12 are a plurality of ribbon guiding rollers 16, 17, 18, 19, and 20 (best shown in Figure 4). Each of these rollers is supported upon a pin 22, which extends between the side flanges 11 and 12, and is secured rigidly thereto by pinning or any other suitable method, as best shown in Figure 5. In our preferred modification, the pin 22 carries a flattened sphere or bead 23 which closely engages the pin 22 so as to ad-

here frictionally to the same in any position in which it may be placed. The roller 20, in this preferred modification, takes the form of a cylindrical sleeve surrounding the sphere or bead 23 in rolling engagement therewith, so that the bead 23 forms a bearing for the sleeve 20, which both permits rotation of the sleeve about its axis and tilting movement transverse to its axis, as shown in dotted lines. The sphere or bead 23 is flattened on those portions of its surface facing the flanges 11 and 12 to permit axial manipulation of bead 23 by a dentist's explorer tool which may be inserted in the space between the end of the roller or sleeve 20 and the adjacent side flange. By means of the explorer tool, the bead may be moved from one end to the other end of pin 22 for a purpose which will be more fully explained later.

While the construction of only roller 20 has been described, it is to be understood that the construction of the other rollers, particularly rollers

17, 18, 19, and 20 is the same. In some cases, roller 16 may be provided with a conventional cylindrical bearing which does not provide for tilting of the roller transverse to its axis, as is the case with the construction just described in connection with roller 20.

Again considering the body member 10, this member terminates at its outer end in an end flange portion 25 which is reversely bent to provide two spaced legs 26 and 27.

Slideably disposed on the body member 10 is a slide member 30, also formed of sheet metal. This member is slideably retained in engagement with body member 10 by a pair of ears 31 and 32, which are bent over to engage the front wall of the member 10.

The slide member 30 has secured thereto a threaded rod 34, which extends through a pair of aligned openings in the legs 26 and 27 of flange 25. A nut 35 having a flange 36 and a knurled knob 37 is in threaded engagement with rod 34. The flange 36 of nut 35 is retained in place between the legs 26 and 27 of body member 10, so that any rotation of the nut 35 by manipulation of knob 37 causes slide member 30 to move longitudinally with respect to body member 10. As will be apparent, this longitudinal movement of slide 30 is employed to vary the size of the loop or loops formed by the matrix ribbon.

The slide member 30 pivotally carries at its inner end a clamp in the form of an L-shaped member 40, having one leg pivotally secured to member 30 and having its other or outer leg provided with a pair of slots 41 and 42. The slots 41 and 42 are designed to receive the ends of a matrix ribbon 44. The ends of the matrix ribbon are threaded first through opening 42 and are then looped back through opening 41. The element 40 is shown in Figure 6 in the position in which it is placed while the ribbon is being threaded through openings 42 and 41. Upon tightening of the ribbon due to the movement of slide 30 to the right, as viewed in the drawing, the clamp 40 is rocked in a counter clockwise direction to cause the ribbon in the openings 41 and 42 to assume a position such as shown in Figure 7 in which the outer end of the outer leg of the clamp 40 is in a straight line with the point of pivotal connection of clamp 40 with slide member 30, and with the general direction of ribbon 44. As will be evident from Figure 7, this position is one in which the loop formed by the ends of ribbon 44 is tightly gripped by the end portion of the upper leg of clamp 40.

Referring now to Figures 1 and 2, the operation of the clamp will be described in connection with the filling of two adjacent teeth. The possibility of using our matrix clamp simultaneously with two adjacent teeth is of considerable importance, as previously explained, inasmuch as cavities commonly occur in two such adjacent teeth. As will be apparent from the drawing, the ribbon 44 is threaded around roller 20 and looped through the space between rollers 19 and 20. The ribbon is then brought around roller 18 and looped through the space between rollers 17 and 18. Finally, the ribbon is looped around roller 16 and brought back to the clamp 40 where the two ends are threaded first through opening 42 and then through opening 41, as previously described. The two loops of the ribbon 44 are then placed over the teeth containing the cavities to be filled, and while the loops of the ribbon are retained in place manually, the nut 35 is tightened up by rotation of knob 37. Due to the fact that both ends of the ribbon

44 are attached to the moveable clamp 40, the ribbon will be simultaneously and equally tensioned about both of the teeth to which it is applied until it closely conforms with the contour of the teeth. As previously explained, the rollers 16 to 20 are provided with bearings which permit them to tilt transverse to their axis, as shown in Figure 5. The purpose of this is to permit the matrix ribbon to conform with the contour of tapered teeth. By locating the bead 23 at one end of pin 22, it is possible for the rollers 16 to 20, and particularly rollers 17 to 20, to adjust themselves to varying degrees of taper.

The matrix ribbon loops may be readily removed from the teeth by loosening the clamp and slipping the loops off. Furthermore, the ribbon can be quickly removed from the clamp by lifting the clamp 40 to the position shown in Figure 6 and pulling the ends of the ribbon first out of slot 41 and then out of slot 42. Thereafter, the ribbon can be readily removed from between the rollers.

Furthermore, as is evident from Figure 3, the ribbon can be used to form a matrix for only one tooth by not forming a loop between one pair of rollers. Thus, in Figure 3, the loop between rollers 17 and 18 has been omitted and the ribbon extends merely on one side of rollers 17 and 18. The same uniform engagement of the ribbon with the tooth is obtained when only one loop is employed as when two loops are employed.

Where it is necessary to reverse the direction in which the clamp is applied to the teeth, as in Figure 3, all that is necessary in order to permit such reversal is to move the bead 23 from one end of the pin 22 to the opposite end. As pointed out earlier, this can be readily done by the insertion of an explorer tool between the roller 40 and the side flange adjacent which the bead 23 is located, and the use of the explorer tool to move the bead 23 longitudinally of pin 22. As evident from Figures 1 and 2, the beads should always be located at the ends of the pins adjacent the point of narrowest width of the teeth, that is, next to the gum line. With the beads in this location as tension is applied to the ribbon, the rollers will tilt to conform with the taper of the teeth, permitting the ribbon closely and uniformly to engage the teeth.

The mounting for the rollers shown in Figure 5 is, as indicated above, the preferred form of our invention. In this arrangement, it is possible to adequately grip teeth of varying characteristics because of the fact that the point of tilting of the roller 20 is adjacent one end. Simpler arrangements are shown in Figures 8 and 9. In these modifications, the side flanges, being identical, have been given similar reference characters. The roller in Figure 8 has been designated by the numeral 20a. In this modification, the roller is supported upon a bearing 45 having the form of a pair of opposed cones. It will be obvious that the roller 20a is not only free to roll about this bearing 45 but is also free to tiltably move about the area of greatest diameter thereof, which area is at the center of the bearing. While this arrangement provides a simple construction which permits shifting of the roller to accommodate irregularities in the teeth, it does not provide the flexibility of the arrangement of Figure 5 and does not permit satisfactory clamping of the band against the tooth where the thickest portion of the tooth is adjacent the middle there-

In the arrangement of Figure 9, the roller has one loops for embracing teeth, a further guide parallel to said pairs of guides and about which the further guide recesses 47 and 48 to permit tilting of the roller, 51 being more remotely located from said clamp member than the pin 22. This arrangement, while extremely simple in nature and permitting a limited member adapted to engage the opposite ends of the matrix ribbon is the ribbon, and means for moving said clamp member subject to the limitations of the arrangement of member with respect to said body member to simultaneously vary the size of said loops to clamp Figure 8.

It will be seen that we have provided a dental clamp them about a plurality of teeth, matrix clamp in which it is possible to uniformly clamp the ribbon about a tooth regardless of the shape of body member having a plurality of pairs of contour of the tooth. It will furthermore be seen normally parallel guides with openings between apparent that we have provided a matrix clamp 15 said guides, a further guide parallel to said pairs by which it is possible to uniformly clamp a plurality of guides, a clamp member movably mounted on matrix ribbon simultaneously about a plurality of said body member, said further guide being more of teeth. It will also be apparent that our clamp is more remotely located from said clamp member than is extremely simple in character and can be set said pair of guides, a single matrix ribbon easily readily assembled.

While we have shown certain specific embodiments of our invention for purposes of illustration, guides and around said further guide back to it is to be understood that our invention is in said clamp member, the ends of said ribbon being limited solely by the scope of the appended claims. 20 being secured to said clamp member, and means

We claim as our invention:

1. A matrix clamp comprising a body member or said body member to vary the size of the loops having a plurality of pairs of normally parallel deformed by the ribbon extending between the guides, said body member being cut away at least 25 between each pair of guides to provide a plurality

of openings, said openings being slightly wider 30 a body member having a plurality of pairs of than a conventional matrix ribbon to permit the normally parallel guides with openings between looping of a single matrix ribbon through said guides, a further guide parallel to said pairs 35 openings to form a plurality of loops for embracing of guides, a clamp member movably mounted on said body member, a matrix ribbon extending member and adapted to engage at least one end of 35 from said clamp member successively around such a ribbon to tension the same simultaneously about a plurality of teeth.

2. A matrix clamp comprising a body member having a plurality of pairs of normally parallel guides, said body member being cut away at least 40 between each pair of guides to provide a plurality of openings, said openings being slightly wider 45 than a conventional matrix ribbon to permit the looping of a single matrix ribbon through said guides being in the form of rollers individually 50 openings to form a plurality of loops for embracing teeth, and means carried by said body member and adapted to engage at least one end of 50

7. A matrix clamp comprising a body member having a pair of normally parallel guides about a plurality of teeth, each of said guides and a further guide normally parallel to the being freely tiltable to enable the ribbon to conform 55 to the contour of variously tapered teeth away between said pair of guides to provide an opening to maintain the tension of the ribbon more 60 opening therebetween, said opening being wider than a conventional matrix ribbon, a clamp member and adapted to engage at least one end of 65

3. A matrix clamp comprising a body member movably mounted on said body member having a plurality of pairs of normally parallel guides, said further guide being more remotely located from said clamp member than said pair at least between each pair of guides to provide a plurality of openings, said openings being slightly wider than a conventional matrix ribbon to permit the looping of a single matrix ribbon through said openings to form a plurality of loops for embracing teeth, a clamp member 60 adapted to engage the opposite ends of such a ribbon, and means for moving said clamp member with respect to said body member to simultaneously vary the size of said loops to clamp them about a plurality of teeth.

4. A matrix clamp comprising a body member having a plurality of pairs of normally parallel guides, said body member being cut away 70 at least between each pair of guides to provide a plurality of openings, said openings being slightly wider than a conventional matrix ribbon to permit the looping of a matrix ribbon through said openings to form a plurality of loops for embracing teeth, a clamp member

8. A matrix clamp comprising a body member having a pair of normally parallel guides and a further guide normally parallel to the guides of said pair, said body member being cut away between said pair of guides to provide an opening therebetween, said opening being wider than a conventional matrix ribbon, a clamp member movably mounted on said body member,

said further guide being more remotely located from said clamp member than said pair of guides, said clamp being adapted to have a matrix ribbon looped through the opening between said pair of guides and around said further guide with the ends attached to said clamp member, said clamp further being provided with means for moving said clamp member with respect to said body member to vary the size of said loop, and said guides all being tiltable with respect to said support to allow the ribbon to conform closely with the tapered contour of a tooth.

9. A matrix clamp comprising a body member having a pair of normally parallel guides, said body member being cut away between said pair of guides to provide an opening therebetween, said opening being wider than a conventional matrix ribbon, a clamp member movably mounted on said body member, said clamp being adapted to have a matrix ribbon looped through the opening between said pair of guides with the ends attached to said clamp member, said clamp further being provided with means for moving said clamp member with respect to said body member to vary the size of said loop, and each of said guides being tiltable about a point close to one end thereof to allow the ribbon to conform closely with the tapered contour of a tooth.

10. A matrix clamp comprising a body member having a pair of normally parallel guides, said body member being cut away between said pair of guides to provide an opening therebetween, said opening being wider than a conventional matrix ribbon, a clamp member movably mounted on said body member, said clamp being adapted to have a matrix ribbon looped through the opening between said pair of guides with the ends attached to said clamp member, said clamp further being provided with means for moving said clamp member with respect to said body member to vary the size of said loop, and each of said guides being in the form of a cylindrical roller journaled on said support member and tiltable with respect thereto.

11. A matrix clamp comprising a body member having a pair of normally parallel guides, said body member being cut away between said pair of guides to provide an opening therebetween, said opening being wider than a conventional matrix ribbon, a clamp member movably mounted on said body member, said clamp being adapted to have a matrix ribbon looped through the opening between said pair of guides with the ends attached to said clamp member, said clamp further being provided with means for moving said clamp member with respect to said body member to vary the size of said loop, and each of said guides being tiltable about a member adjustable over the full length of said guide so that the point of tilting may be selected.

12. A matrix clamp comprising a body member having a pair of normally parallel guides, said body member being cut away between said pair of guides to provide an opening therebetween, said opening being wider than a conven-

tional matrix ribbon, a clamp member movably mounted on said body member, said clamp being adapted to have a matrix ribbon looped through the opening between said pair of guides with the ends attached to said clamp member, said clamp further being provided with means for moving said clamp member with respect to said body member to vary the size of said loop, and each of said guides being in the form of a hollow cylinder journaled upon and tiltable about a bead frictionally mounted on a shaft and movable longitudinally of the shaft and cylinder.

13. A matrix clamp comprising a body member having a means thereon for securing the opposite ends of a matrix ribbon thereto to form a loop engageable about a tooth and means for tightening said loop, and a guide for said ribbon consisting of a hollow cylindrical roller journaled upon and tiltable upon a bead frictionally mounted on a shaft and movable longitudinally of the shaft and cylinder.

14. A matrix clamp having a body member and a clamp member movably mounted thereon for securing the opposite ends of a matrix ribbon thereto to form a loop engageable about a tooth, means for moving said clamp member with respect to said body member to vary the size of said loop, said clamp member consisting of a pivoted element having a pair of ribbon receiving slots therein, and a matrix ribbon secured to said body member and having both ends thereof passed together through said ribbon receiving slots in sequence, said clamp member being effective upon tension being applied thereto by operation of said previously named means to swing in a direction to grip the ribbon extending through said slots.

15. A matrix clamp comprising a body member having a plurality of pairs of normally parallel guides, said body member being cut away at least between each pair of guides to provide a plurality of openings, said openings being slightly wider than a conventional matrix ribbon to permit the looping of a single matrix ribbon through said openings to form a plurality of loops for embracing teeth, and means carried by said body member and adapted to engage at least one end of such a ribbon to tension the same simultaneously about a plurality of teeth, each of said guides being freely tiltable about one end thereof to enable the ribbon to conform to the contour of variously tapered teeth and to maintain the tension of the ribbon more nearly uniform over the width of the ribbon.
